JUG

Thomas W. Mullen, Claremont, Calif., assignor to
Celanese Corporation of America, New York, N.Y.,
a corporation of Delaware

Filed Nov. 13, 1962, Ser. No. 72,456

Term of patent 14 years

(Cl. D58—5)

FIG. 1 is a side elevation of a jug, showing my new design;

FIG. 2 is a rear elevation thereof;

FIG. 3 is a front elevation thereof; and

FIG. 4 is a top plan view thereof.

The characteristic features of my design reside in a jug having end wall portions curving inwardly between opposite ends of the container at non-diametrically opposed locations, the location along one end wall providing the lower terminus for the container handle which

curves upwardly to the top, said handle being mounted upon a substantially flat end wall, all as shown.

I claim:

The ornamental design for a jug, as shown and described.
